UNITED STATES PATENT OFFICE.

JACQUES WORTH, OF PARIS, FRANCE.

DESIGN FOR A COMBINED BOTTLE AND HOLDER THEREFOR.

Application filed March 3, 1927. Serial No. 20,949. Term of patent 14 years.

To all whom it may concern:

Be it known that I, JACQUES WORTH, a citizen of the Republic of France, residing at Paris, France, have invented a new, original, and ornamental Design for Combined Bottle and Holder Therefor, of which the following is a specification, reference being had to the accompanying drawing, forming part thereof.

Figure 1 is a front view in perspective of a combined bottle and holder therefor, showing my new design, and

Fig. 2 is a rear view thereof in perspective.

I claim:

The ornamental design for a combined bottle and holder therefor, as shown.

JACQUES WORTH.
